[57] CLAIM

The ornamental design for a bathware support bracket, as shown and described.

DESCRIPTION

FIG. 1 is a perspective view of a bathware support bracket showing my new design;

FIG. 2 is a top plan view thereof;

FIG. 3 is a front elevational view thereof;

FIG. 4 is a side elevational view thereof, the opposite side being a mirror image of that shown;

FIG. 5 is a bottom plan view thereof; and

FIG. 6 is a rear elevational view thereof.
